UNITED STATES PATENT OFFICE.

WILLIAM HAMILTON, OF ALLEGHENY, PENNSYLVANIA.

DESIGN FOR A CASKET.

SPECIFICATION forming part of Design No. 28,255, dated February 1, 1898.

Application filed March 5, 1897. Serial No. 626,145. Term of patent 14 years.

To all whom it may concern:

Be it known that I, WILLIAM HAMILTON, of Allegheny, in the county of Allegheny, and State of Pennsylvania, have invented a new and useful Design for Caskets, of which the following is a full, clear, and exact description, reference being had to the accompanying drawings, forming part of this specification, in which—

- o Figure 1 is a perspective view of a burial-casket embodying my design, and Fig. 2 is a vertical cross-section of the same.

My design consists in a burial-casket having the interior contour and shape, as shown in the drawings and hereinafter described.

In the drawings, 2 represents the body of a casket, and 3 3 cove-sections, which extend outwardly from the panels 4. As shown, the interior surfaces of the casket flare or incline outwardly, giving an urn shape to such interior.

I claim—

The design for a casket substantially as herein shown and described.

In testimony whereof I have hereunto set my hand.

WILLIAM HAMILTON.
